UNITED STATES PATENT OFFICE.

ERVIN BOWKER, OF FALL RIVER, MASSACHUSETTS, ASSIGNOR OF ONE-HALF TO
ARTHUR E. BOULAIIS, OF FALL RIVER, MASSACHUSETTS.

RIVETER.

Application filed August 11, 1923. Serial No. 656,865.

To all whom it may concern:

Be it known that I, ERVIN BOWKER, a citizen of the United States, residing at Fall River, on the county of Bristol and State 5 of Massachusetts, have invented certain new and useful Improvements in Riveters, of which the following is a specification.

This invention relates to means for riveting studs in bobbin-driving gears. In the 10 manufacture of yarn, the slubber, intermediate and roving frame bobbins are all driven by individual cast iron gears, the bobbin resting at its lower end upon a shoulder on the gear and being provided 15 with a groove or slot engaging a stud on said shoulder. The stud is riveted through the shoulder and the riveting operation is now generally performed by hand. As the riveting or up-setting operation must be performed 20 in the small space between the shoulder and the teeth of the gear, it is practically impossible to rivet the stud satisfactorily with the use of ordinary hammers, and hand-riveted studs work loose in a very 25 short time so that it is impossible to use bobbins in which the grooves are even slightly worn inasmuch as the bobbins will ride and jump over the stud and make imperfect yarn. The shell of the gear is very thin and if the 30 riveting hammer slips very slightly it will strike the shell and the gear will be broken. Under these conditions, a careful machinist can rivet only a very small number of gears in a given period and he will break from 35 one-sixth to one-fourth of the total number of gears so that the work is not only slow but is costly inasmuch as the riveting of the stud is the last operation in the making of the gear and when a gear is broken the cost 40 of the same is a complete loss. It is the object of my invention to provide a simple, inexpensive and easily operated device by the use of which an unskilled operator can rivet a large number of studs within a given 45 period without breaking any of the gears while at the same time the stud will be set more firmly in the gear than has been possible heretofore. The stated object and other objects which will incidently appear 50 in the course of the following description are attained by the use of such a device as is illustrated in the accompanying drawings, and the invention resides in certain novel features which will be particularly pointed 55 out in the appended claims.

In the drawings:

Figure 1 is a side elevation, partly broken away, of my riveting machine, a gear being shown therein in section in position to have the stud riveted;

Fig. 2 is a plan view thereof, the gear being omitted;

Fig. 3 is a longitudinal vertical section on the line 3—3 of Fig. 2;

Fig. 4 is a detail perspective view of the 65 hammer looking at the under side thereof;

Fig. 5 is a sectional view of the post and the member of the handle cooperating therewith;

Fig. 6 is a detail perspective view of the 70 anvil;

Fig. 7 is a view of a bushing which may be employed, and

Fig. 8 is a plan view of another form of anvil.

In carrying out my invention, I employ a bed plate 1 which may conveniently be of the oblong form shown most clearly in Fig. 2, and is provided at its corners with supporting legs or feet 2 and at one end with a central pillar 3, the pillar and the feet being preferably cast integral with the bed plate. Formed in the bed plate in alinement with the pillar is a longitudinal slot 4, and in the sides of the pillar at the inner edge 85 edge thereof are recesses or notches 5. A hammer 6 is provided, and this hammer is preferably a block of steel having one end forked, as shown at 7, to engage around the inner edge of the pillar 3 and fit within the 90 recesses 5, a pivot pin 8 being inserted through the members of the fork and through the pillar to secure the hammer in place. The free end of the hammer is preferably slightly arcuate, as shown at 9, so 95 that it may fit around the shell of the gear being operated upon and in the under side of the hammer adjacent the free arcuate end of the same I form a series of circular grooves 10, the function of which will presently appear. Adjacent the forked end of the hammer, a recess 11 is formed in the under side thereof, and this recess receives the upper end of a spring 12 which is disposed between the hammer and the bed plate 100 and is centered by the stud or pin 13 secured in the bed plate, as clearly shown. The spring holds the hammer against dropping and is itself held in proper position at all times by the recess 11 and the pin or stud 110

13 in an obvious manner. In the upper side of the hammer is provided a recess or socket 14 in which is engaged the lower end of a striker 15 which is supported in an inclined 5 position by a guide block 16 secured upon the upper end of the pillar 3. The striker is preferably provided with an enlarged head 17 to receive the blows of a hammer or other tool and it plays in a slot or passage 10 18 within the guide block, as shown clearly in Fig. 3. The guide block is preferably formed separately from the pillar and removably secured thereto by a cap screw 19, but it will, of course, be understood that it 15 may be formed integral with the pillar. Below the hammer, an anvil 20 is secured upon the bed plate, the anvil consisting of a block of steel provided with a groove 21 in its upper side. This groove in use receives 20 the head of the stud to be riveted and as the studs vary somewhat in size it is found desirable to have the different ends of the grooves of different depths, as shown in Figs. 3 and 6. It may sometimes be desirable to provide 25 a plurality of grooves, and in Fig. 8 I have shown an anvil 22 having four grooves 23 in its top, each groove extending from one side of the anvil to the center thereof and no two of the grooves being of the same depth. 30 The sides of the anvil may be straight or arcuate, the only essential being that it extend close enough to the gear to properly support the rivet. Fig. 6 shows an anvil having a curved wall and Fig. 8 shows a 35 straight wall.

I also employ a post 24, the upper portion of which is circular in cross section and is adapted to fit within the bore 25 of the gear, shown at 26. The post 24 is constructed with an annular shoulder 27 upon which the gear rests during the riveting operation and, below the said shoulder, the post is provided with a flat-sided portion 28 adapted to fit within the slot 4 of the bed 40 plate and thereby hold the post against rotation relative to the bed plate. Upon reference to Fig. 2 more particularly, it will be noted that the shoulder 27 not only supports the gear upon the post but also supports the post upon the bed plate. The lower extremity of the post is threaded, as shown at 29, and an adjusting handle is mounted upon the said threaded extremity. This handle 45 may be of any convenient form and preferably consists of a head or nut portion 30 which is suitably threaded internally to engage the threaded extremity 29 of the post. The said body or nut portion of the handle is constructed with an internally threaded 50 socket 31 in which is engaged the inner end 55 of the lever member 32 of the handle, the said lever member projecting out from under the bed plate so that it may be easily 60 grasped by the workman in the operation 65 of the machine.

The post 24 is formed with a diameter which will permit it to pass within the bore of the smallest gear while the shoulder 27 is of such a radius that it will accommodate the largest gear. When the larger gears are to 70 be riveted, a bushing or sleeve 33 may be placed around the post and supported upon the shoulder 27 so that the gear which will be fitted over the bushing will be supported 75 concentrically with the post.

It is thought the use of the device will be readily understood. In assembling the parts, the nut or head member 30 of the adjusting lever is turned up on the end of the post until it reaches such a point that 80 a quarter turn will secure or release the post. The lever member of the handle is then engaged in the socket 31 and the device will be ready for use. When the handle is in the position shown in Figs. 1 and 2, the post is 85 free to slide in the slot 4. The post is then pushed forward in the slot, the gear, indicated at 26, is placed over the post in inverted position and the post with the gear thereon is then drawn rearward until the 90 shell of the gear abuts the free end of the hammer 6, the shoulder 34 of the gear passing between the hammer and the anvil and the head of the stud 35 resting in the groove 21 of the anvil. The lever handle is then 95 swung forwardly so that the nut or head 30 thereof will bind against the under side of the bed plate and thereby secure the post against movement, at the same time swinging the lever out of the way of the operator. 100 A few light blows from a hammer may then be delivered upon the head 17 of the striker 15 and the force of these blows will be expended through the hammer 6 upon the end of the rivet so as to upset the same, and it 105 has been found that the provision of the grooves 10 very materially expedites the upsetting of the ends of the rivet. The lever 32 is then swung rearwardly, releasing the post so that it may be again pushed forward 110 in the slot 4, the gear removed and another gear substituted; the operation being repeated indefinitely until all the gears to be riveted have been treated.

From the foregoing description, taken in 115 connection with the accompanying drawings, it will be seen that I have provided an exceedingly simple tool whereby the work of riveting the studs to the gears will be very expeditiously and efficiently performed, 120 and it has been demonstrated that a large number of studs may be riveted in a given period by the use of my machine by a comparatively unskilled workman without breaking any of the gears.

Having thus described the invention, what is claimed as new is:

1. An apparatus for the purpose set forth comprising a gear supporting post, an anvil arranged adjacent the post to engage under 130

the shoulder of a gear carried by the post to support a stud fitted in said shoulder, a hammer mounted above the anvil to bear upon the end of the stud resting on the anvil, and a striker bearing upon the hammer.

2. An apparatus for the purpose set forth comprising a post to support a gear, an anvil arranged adjacent the post and provided in its upper side with a groove to receive a stud engaged in the shoulder of a gear carried by said post, a hammer disposed above the anvil and arranged to rest upon the end of the stud, a striker bearing upon the upper side of the hammer, and yieldable means for holding the hammer in a raised position.

3. An apparatus for the purpose set forth comprising an anvil having a stud-receiving groove in its upper side, a hammer pivotally supported above the anvil and adapted at its free end to bear upon a stud resting on the anvil, a striker bearing upon the upper side of the hammer, yieldable means for holding the hammer raised, and means for supporting a gear adjacent the anvil and the hammer with a shoulder on the gear fitting between the hammer and the anvil, and a stud engaged in said shoulder supported by the anvil.

4. An apparatus for the purpose set forth comprising an anvil, a hammer mounted above the anvil, a striker bearing upon the upper side of the hammer, a post adapted to support a gear adjacent the hammer and the anvil with a shoulder on the gear projecting between the anvil and the hammer and a rivet engaged in said shoulder resting upon the anvil, and means for shifting said post to and from the hammer and the anvil.

5. An apparatus for the purpose set forth comprising a bed plate having a longitudinal slot therein, a gear-supporting post

movably mounted in said slot and having a flat-sided portion within the slot whereby rotation of the post will be prevented, a handle having a body portion in threaded engagement with the lower end of the post whereby to shift the same along the slot and secure it in a set position between the ends of the slot, an anvil secured upon the bed plate in position to cooperate with the post, a hammer mounted above the anvil, and a striker supported above and bearing upon the upper side of the hammer.

6. An apparatus for the purpose set forth comprising a bed plate having a longitudinal slot in one end portion and a pillar rising from its opposite end portion, a hammer pivotally attached to the pillar at the inner edge thereof, yieldable means for supporting the hammer in a raised position, an anvil secured upon the bed plate between the slot and the pillar and below the hammer, a guide block carried by the upper end of the pillar, a striker supported obliquely in said guide block and bearing upon the upper side of the hammer, a post supported upon the bed plate and having a portion passing through the slot in the bed plate, and a handle member having threaded engagement with the lower end of the post below the bed plate whereby to shift the post along the slot and to bind the post against the bed plate.

7. Apparatus for riveting a stud in a shoulder on a gear comprising means for supporting the gear, means to support the stud in the shoulder of the gear, a hammer resting on the stud above the shoulder of the gear, and means for applying upsetting force to the hammer.

In testimony whereof I affix my signature.

ERVIN BOWKER. [L. s.]
